ERNEST H. PASQUÉ, OF DETROIT, MICHIGAN.

MASSAGE APPARATUS.

Application filed December 30, 1925. Serial No. 78,341.

My invention relates to improvements in massage, vibratory or percussor apparatus for therapeutic health and beauty treatment.

Apparatus of this character is widely used 5 in spondylotherapy massage and general mecanotherapy. In treatments of this kind it is highly desirable that the percussor or vibrator deliver a sharp, quick blow to the surface of the body treated irrespective of 10 the time interval between blows. No matter how long the lapse of time between blows, each blow of the percussor head or impact member should be a sharp, quick blow. The blows should also be delivered at evenly 15 timed intervals.

In apparatus of this kind now in use the percussor head is usually actuated by a crank or eccentric whereby the force and character of the blow delivered is determined entirely by the rate of travel during 20 the complete stroke of reciprocation, and therefore, bears a direct ratio between the elapsed time interval between blows. If the blows are being delivered rapidly they are 25 sharp and quick. If they are being delivered slowly or with a substantial lapse of time between each blow they are not sharp and quick.

My improved apparatus is so constructed 30 that without regard to the elapsed time between blows each blow delivered is a sharp and quick one. The characteristic quality and force of the blow of my improved apparatus is in no wise dependent upon the successive rapidity of the blows.

Another distinguishing quality and important object of my invention is that the blows delivered are yieldable to the resistance imposed thereagainst. In instruments 40 of this type now in use the percussor plunger is forced to travel a determined distance which is measured by the throw or radius of its actuating crank or eccentric. This produces an unsatisfactory result in that injury 45 may be caused if the blows are applied to body areas where the bones are not well covered with soft tissue. The impact of the percussor head of my improved device is of such a character as to yield to the resistance 50 imposed by the surface impinged. The length of the stroke of the percussor plunger is not fixed. The operator through suitable manipulation of the device may deliver quick blows in the nature of licks or slaps 55 or the blows may be of a vibratory character.

The above objects and advantages together with others will more fully appear from the following description of suitable embodiments of my invention illustrated in 60 the accompanying drawings and defined in the appended claims.

In the drawings,—

Fig. 1 shows the complete device in use 65 in a spinal treatment.

Fig. 2 is an elevation of the instrument with a portion of the casing removed.

Fig. 3 is a side elevation of part of the operating mechanism.

Fig. 4 is a side elevation of one of the eccentric cams.

Fig. 5 is a vertical sectional view through the structure shown in Fig. 1.

In the drawing I have shown a manually operable portable type of device provided 75 with a suitable handle 10 and a casing shell 12 having a removable front plate 14 which may be held in position by means of screws 16. The casing shell 12 is extended as at 18 to form a support for an electric motor 20. 80 A connection 22 is shown as leading to the motor and the motor itself has a drive shaft 24 suitably supported within bearings 26 and terminating in a worm screw 28 which engages a worm gear 30 mounted upon the 85 shaft 32 to drive the same. The shaft has a bearing at each end in the wall of the casing member 12 as shown at 34.

I provide a plunger 36 which is internally threaded at its lower end as at 38 to receive 90 the threaded portion 40 of an impact member or head portion 42. Impact heads 42 may be provided in different sizes and shapes to suit the needs of the purpose to which they are to be put.

The plunger travels through a bearing 44 in the lower end of the casing and is provided with a stop flange 46 adapted to seat thereagainst to limit the downward movement of the plunger. The upper end of the 100 plunger extends through a bearing 48 in the upper wall of the casing, as shown in Fig. 5, and a seat 50 is secured to the upper end of the plunger within which is positioned one end of a coil spring 52, the opposite end of which is engaged within a screw-threaded cap 54 which threads into the annular chamber 56 that contains the spring. The screw-threaded cap has a knurled outer periphery 58 by means of which it may be adjustably 105 threaded into or out of the casing 56 to increase or lessen the tension on the spring.

The plunger is formed with an intermediate portion consisting of a pair of spaced-apart arms 60 which are curved as shown in Fig. 3 of the drawing. Each arm carries upon a pin 62 a roller bearing 64. There is mounted upon the shaft 32 a pair of rotatable eccentric cams 66 of the shape shown in Fig. 4, so mounted that when the rotation of the shaft and therefore the cams is in a clockwise direction the projecting eccentric portion 68 of each cam as it travels over the roller 64 serves to lift the plunger against the resistance of the spring 52. As the point of this projecting eccentric portion 68 trips over the roller 64 the plunger is released to the action of the constrained spring 52 and the spring throws the plunger downwardly to the limit of its projected stroke. The action of the plunger is similar to that of a hammer. It is withdrawn at a determined rate of speed and at determined timed intervals dependent upon the speed of the motor for a fixed distance. It is thrown forward, however, under the action of the spring at a rate of travel entirely independent of its rate of withdrawal. Therefore, the number of strokes or blows delivered by the impact head 42 in a given period of time has no effect upon the force or character of the blow. The force and character of such blow is determined by the action of the spring which is so arranged that the impact member will deliver a sharp, quick blow irrespective of the number of blows delivered thereby within a given period.

The operator in employing the apparatus may so manipulate the device as to remove the weight thereof from the surface of the body and also may so manipulate the device as to produce a succession of sharp, quick blows or a series of vibratory impacts. The plunger may be permitted to lift entirely from the surface of the body or it may at all times be held thereagainst. The downward travel of the plunger produced by the expansion of the spring may be limited by

the resistance imposed from the surface treated, and in all cases the impact delivered possesses its essential characteristic qualities which are in no wise dependent upon its rate of withdrawal.

What I claim is:

1. In a power driven massage percussor instrument, a plunger supported for reciprocation, a percussor head carried thereby, a spring exerting tension on said plunger, a power driven shaft, a pair of spaced apart cams on said shaft, said plunger provided with a forked intermediate portion bowed about said shaft, a roller on each fork of said plunger adapted to engage a cam on said shaft whereby the plunger is actuated against the tension of said spring upon rotation of the cam.

2. In a power driven massage percussor instrument, a casing, a power driven shaft rotatably mounted transversely within the casing, a pair of separated cams on said shaft, a plunger mounted within the casing for reciprocation on a line perpendicular to the axis of the shaft and having a forked bowed intermediate portion provided with a roller upon each fork engaged with a cam on the shaft, a spring tensioned to hold the plunger to maintain the rollers in contact with the cams on the shaft, said casing provided with a cup like portion at its upper end having a removable end closure, said plunger provided with a removable end portion mounted within said cup like portion of the casing and having a bearing therein, a spring within said cup like portion engaging at one end the removable end of the plunger and at the opposite end the end closure of said cup like portion, said end closure of the cup like portion being adjustable with respect thereto to vary the tension of said spring.

In testimony whereof, I sign this specification.

ERNEST H. PASQUÉ.
